UNITED STATES PATENT OFFICE.

GEORGE LAURITS EILERT, JR., OF NEW YORK, N. Y.

DESIGN FOR A BUTTON, BADGE, BANNER, OR ARTICLE OF SIMILAR NATURE.

57,215.

Specification for Design.

Patented Mar. 8, 1921.

Application filed February 20, 1920. Serial No. 360,158. Term of patent 3½ years.

To all whom it may concern:

Be it known that I, GEORGE LAURITS EILERT, Jr., citizen of the United States, and resident of New York city, in the county of New York and State of New York, have invented a new, original, and ornamental emblematic Design for Button, Badge, Banner, or Article of Similar Nature, of which the following is a specification, reference being had to the accompanying drawings, forming part thereof.

The figure is a plan view of a button, badge, or similar article embodying my new design.

I claim:

The ornamental emblematic design for a button, badge, banner or article of similar nature.

Signed at New York city, in the county of New York, and State of New York, this 12th day of February, A. D. 1920.

GEORGE LAURITS EILERT, JR.
